UNITED STATES PATENT OFFICE

107,524

DESIGN FOR A CAPE

Benjamin Lefrak, New York, N. Y.

Application November 4, 1937, Serial No. 72,610

Term of patent 3½ years

To all whom it may concern:

Be it known that I, Benjamin Lefrak, a citizen of the United States of America, residing in New York city, in the Borough of Manhattan, county and State of New York, have invented a new, original, and ornamental Design for a Cape, of which the following is a specification, reference being had to the accompanying drawing, forming part thereof, wherein,

The handkerchief is permanently attached to the garment, as shown.

I claim:

The ornamental design for a cape, substantially as shown, and described.

BENJAMIN LEFRAK.
